(57) **CLAIM**

The ornamental design for an electronic calculator as shown and described.

DESCRIPTION

FIG. 1 is a reduced-scale front, right side perspective view of an electronic calculator showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The portions depicted by broken lines are for illustrative purposes only and form no part of the claimed design.

The dash-dot broken lines define the bounds of the claimed design and form no part thereof.
